UNITED STATES PATENT OFFICE.

MAX ROSENSTOCK, OF PATERSON, NEW JERSEY.

MANUFACTURE OF FABRICS.

1,366,705.

Specification of Letters Patent. Patented Jan. 25, 1921.

No Drawing.

Application filed June 3, 1920. Serial No. 386,263.

To all whom it may concern:

Be it known that I, MAX ROSENSTOCK, a citizen of the United States, residing at Paterson, in the county of Passaic and State 5 of New Jersey, have invented certain new and useful Improvements in the Manufacture of Fabrics, of which the following is a specification.

This invention relates to that class of silk 10 fabrics, and particularly crapes, in which a crape or crinkled effect is produced by putting a high or crape twist in the silk yarn and after the piece is woven treating it in the process of dyeing to a boiling-off bath 15 whereby to cause a shrinkage of the thus high-twisted yarn, so that it will be left craped or crinkled in the piece. It has heretofore been impossible by any known method to produce a crape or the like silk 20 fabric that would have the very much desired changeable-color effect, because the craping or crinkling depends on the shrinkage taking place in the piece, and if the yarn were first subjected to the dyeing process so 25 as to be dyed in different colors, to be then woven into a fabric, the shrinkage would not only have about, if not altogether, expended itself before weaving but the craping or crinkling which it produces would be taken 30 out of it in the weaving process as the result of tension exerted thereon in the loom.

The object of this invention is to produce a fabric of the class indicated which will give a changeable color effect.

35 To this end I fast-dye a part of the silk yarn which is to compose the fabric. Usually the dyeing of this part of the yarn will shrink it; but my invention is not concerned with or dependent upon any shrinking or 40 non-shrinking of this part of the yarn.

The thus fast-dyed part of the yarn is then interwoven with the remaining part of the silk yarn which is to be woven into the fabric. But this remaining part of such 45 silk yarn is a yarn which when boiled-off will undergo shrinkage, preferably by being high-twisted so that a good craping or crinkling thereof will be an incident of the shrinking.

50 The fabric is then subjected to a boiling-off treatment. Or I may proceed further and then subject the fabric to a dye bath of a different color form that which the first part of the yarn was dyed. The boiling-off to

which the fabric or piece is treated will 55 shrink the second part of the yarn, thus producing the desired crape or crinkled effect in the finished fabric.

As the result of this treatment two effects will be produced in the fabric: First, the 60 boiling-off to which the fabric or piece is treated will shrink the second part of the yarn, thus producing the desired crape or crinkled effect in the finished fabric. Second, the fabric will possess the desired 65 changeable-color effect, because the first part of the yarn is dyed one color and the second part of the yarn has another color—that is, either its natural color or the color which is imparted thereto when, following the boiling-off, the fabric or piece is subjected to a dye bath, as explained. The dye of this latter dye bath will not affect, that is, color, the first part of the yarn, because this yarn 70 was fast-dyed and so will take no more dye. 75

It will be understood that the weaving is done in some usual way so as to produce the changeable-color effect incident in changeable-color fabrics to the yarns of different colors both coming to one face of the fabric 80 and appearing intermingled at such face and so that one will be visually the more prominent from one point of view and the other visually the more prominent from another point of view of said face of the fabric, as 85 by weaving in one of the aforesaid parts of the yarn as warp and the other of said parts as weft.

I do not wish to be restricted to the specific procedure herein set forth, what I claim 90 being:

1. The herein-described method of producing a changeable-color crape-like silk fabric which consists in fast-dyeing silk yarn a given color, then weaving such yarn with 95 other silk yarn capable of shrinkage and so as to produce a fabric in which both such yarns will come to one face thereof intermingled with each other but one will be visually the more prominent from one point 100 of view and the other visually the more prominent from another point of view of said face of the fabric, and then shrinking said other yarn in the fabric.

2. The herein-described method of producing a changeable-color crape-like silk fabric which consists in fast-dyeing silk yarn a given color, then weaving such yarn with 105

other silk yarn which will shrink in a boiling-off treatment and so as to produce a fabric in which both such yarns will come to one face thereof intermingled with each other but one will be visually the more prominent from one point of view and the other visually the more prominent from an-

other point of view of said face of the fabric, and then subjecting the fabric to a boiling-off process, whereby to shrink said other yarn.

In testimony whereof I affix my signature.

MAX ROSENSTOCK.
